Application October 30, 1939, Serial No. 302,033

19 Claims. (Cl. 57—32)

My invention relates to the production of cord, reed, rope, yarn and the like from strip paper or equivalent material by twisting, and more particularly provides a novel and improved method and machine for performing the twisting operation.

The product of the machine and method, which will be hereinafter designated a cord, is used in numerous arts and is made in different forms depending on the use to which it is to be put. To simplify the explanation of the present invention, this specification will describe a method and a machine for making a typical form of cord. Variations in the method and the mechanism, to produce modified forms of product, are within the scope of the invention.

The embodiment of the invention selected for illustrative purposes twists a single flat strip of paper to produce a single cylindrical cord. Products of this general description are quite old, but heretofore their manufacture has been beset with difficulties and the cord has not been as perfect as could be desired.

A principal object of the present invention is to eliminate these manufacturing difficulties and improve the product.

Heretofore the best cords have been made from paper strip that was wetted during or just prior to the twisting operation. The water was necessarily carried into the product and its subsequent evaporation worked undesirable changes in the cord. The difficulties resulting from the twisting of paper in a wet condition were manifold. It was impractical to dry the newly twisted wet cord before winding it on the large reel on which the product is delivered to the consumer. The cord was therefore wound on the reel in wet condition and it dried unevenly. While the exterior of some of the cord would dry fairly well, the interior, along the axis of the cord, would remain wet for a long period of time. The part of a long cord which was initially received on the reel might never dry appreciably since it was almost perfectly protected from the atmosphere by the numerous overlying layers of subsequently wound cord. Cord reeled in wet condition strongly tended to take a set conforming to the curvature about which it was wound. The addition of water increased considerably the weight of the product, which is in and of itself a serious objection when large quantities are being handled, and the difficulty was aggravated by the universal practice of selling paper cord on a weight basis. A fifty pound reel of wet wound cord would contain an average of ten pounds of water, for which the purchaser would pay at the paper poundage rate, and after a period of storage the partially dried cord would weigh less, the difference between the original and final weights constituting a direct loss to the purchaser. A further disadvantage of

a wet wound cord results from its increased diameter. A longer length of dry cord can be wound on a given reel and its weight and length will remain substantially constant.

An important feature of the invention therefore is the provision of means and a method of twisting paper strip without materially wetting it. In lieu of wetting, the invention substitutes a treatment which softens the material better than can be done by wetting. The newly twisted cord is substantially dry and, even if reeled immediately, remains practically perfectly uniform in respect of size, weight and surface texture and appearance.

According to the invention steam is substituted for the water treatment of the prior art. The twisting of the strip is effected in an atmosphere of live steam which softens the paper to a condition in which it can be readily twisted to take a permanent set while remaining quite dry.

As will be explained, an alternative procedure, or a modification of the essential process, comprises pulling the newly twisted cord through a forming and polishing die while its exterior surface only is wetted. The water through which the already twisted cord is subjected but momentarily in this form of the process does not penetrate the cord and functions principally to lubricate it in its passage through the die and eliminate the loud screeching noise that the otherwise dry rubbing surfaces of cord and die would produce. The surface wetting also aids the die in finishing the cord with a dense, glossy surface. Because the steamed cord is hot when this water is applied, and because the water also is preferably hot and does not penetrate the cord, and because substantially all of it is rubbed off by the die, the cord is quite dry by the time, which may be only a few seconds later, it becomes wound on the receiving reel. This use of water in my process is therefore very different from, and not to be confused with, the prior art wetting of the strip to be twisted.

Other objects and advantages of the invention are concerned with improving details of the method and machine and will be clear from the following description of the preferred method and means.

In the accompanying drawings, which depicts a machine which I have built and successfully operated and which therefore may be taken as illustrative of one mode of practicing the invention, and which is not to be considered as in any way limiting the scope of the claims to the precise arrangement shown,

Figure 1 is an elevational view of the machine, taken from what may be regarded as the right-hand side;

- Fig. 3 is a top plan view;
 Fig. 4 is an elevational view of the front end;
 Fig. 5 is a detail vertical sectional view taken through part of the front end structure of the machine, along the line 5—5 of Fig. 6;
 Fig. 6 is a horizontal sectional view taken along the line 6—6 of Fig. 5;
 Fig. 7 is a horizontal sectional view of a detail of the mechanism for threading the cord product on the receiving reel, showing the parts in one position;

Fig. 8 is similar to Fig. 7 but shows the parts in another position; and

Fig. 9 is a side elevational view of another detail of the threading mechanism.

In this machine, a main horizontal frame or bed is provided by two angle iron sides 10 and 11, connected by front and rear end bars 12 and 13, and mounted on four legs 14. Additional main frame cross bars 15 and 16 connect the sides near the front and rear end bars to form a front and a rear bed, respectively. Mounted at the opposite sides of the rear bed are pedestals 17, 18, between which, fairly close to pedestal 17, is a third pedestal 19. A short longitudinal frame member 20 projects from the bars 12 and 15 in the line of the pedestal 19, and from the inner end of this member 20 a post 21 rises, and a similar post 22 is mounted directly opposite it on the side member 10. Lengthwise bars 23 and 24 connect the post 21 and pedestal 19 and the post 22 and pedestal 17, respectively, and a pair of cross bearers 25 on the bars 23 and 24 form a base for a main driving motor 26. This assembly completes the horizontal framing of the machine.

At the front end of the machine I provide a vertical frame formed of a righthand side upright 27 and a lefthand side upright 28 connected across their tops by a cross bar 29 and bottomed on the sides 10 and 11, conveniently between end bar 12 and additional main frame cross bar 15. Diagonal braces 30 and 31 connect the top cross bar 29 with the pedestals 17 and 18, respectively. This assembly completes the main vertical framing at the front end of the machine.

Mounted in the two framings are the operating parts of the machine, comprising a supply of paper strip, a steaming chamber, twisting mechanism, traction sheaves, reeling mechanism including a threading device, and drive connections from the motor 26, all of which, with certain ancillary devices, will now be described.

The motor 26 is connected by a belt 32 with pulley 33 loose on a short main drive shaft 34 which is journaled in a supplemental upright frame. This frame consists of a base 35 which is mounted on bars 12 and 15 and which may be made as a single integral casting with risers 36, 37, and a connecting top 38. There is a bearing 40 for the main drive shaft 34 in the riser 37, and another in a bracket 39 which is bolted to that riser. A hand wheel 40 which is fast on the outer end of the shaft 34 has clutch teeth which cooperate with clutch teeth in the hub 41 of pulley 33. A clutch handle 42 slides the driving member 41 of the clutch into or out of engagement with the driven member 40. Thus the shaft 34 is powered at the will of the operator, by the continuously operating motor 26.

Fast on the inner end of the shaft 34 is a bevel gear 43 for driving the twisting element, which is a heavy plate 44 having a hub 45 socketed in the top 38 of the supplemental upright frame. The hub may be counterbored to receive antifriction bearings 46, and the inner edge of the hub is

provided with bevel gear teeth 47 meshed with the gear 43. An inverted conical forming element 48 sets in an axial opening in the plate 44 and projects through the hub therein and through an aligned opening in the top 38 of the supplemental upright frame, and a replaceable die 49 is mounted in the lower end of the conical forming element. It will be apparent that a strip of paper carried by the plate 44 will be twisted into cord form by rotation of the plate and in such form may be pulled through the die 49.

To mount a supply of paper on the plate 44, I provide the plate with a pair of upright posts 50, 50, connected by a top cross member 51 which carries an upwardly projecting stem 52 journaled in the cross bar 29 of the main vertical frame. The axis of this stem is aligned with the bore of die 49, so that the plate can be rotated about this axis. Because the posts 50 must bear the weight of a considerable quantity of paper strip material and transmit this weight to the plate 44, which of course should be well balanced for smooth rotation, I find it convenient to fix the posts in the plate symmetrically on opposite sides of a diameter of the plate 44. Bearing blocks 53, 54 are slidable on the posts, and each block has a laterally projecting bracket which mounts the shaft 55 of a disc 56 of rolled paper strip material. A set screw fixes the position of each block on its post, and the blocks are arranged so that their brackets project oppositely, each toward the plane of that diameter of the plate 44, on opposite sides of which the posts 50, 50 are set. The shaft 55 of the paper disc is thus in the plane of that diameter, or it intersects it at the middle of the disc, so that the disc is symmetrically arranged with respect to the plate, as are the posts 50, 50, and the weight of all these parts is well balanced on the disc. This arrangement also disposes the top cross member 51 symmetrically across the diameter in question, and brings the center point of the member 51, which is in the axis of the stem 52, into alignment with the axis of rotation of the plate 44.

A drag weight 57, in the form of a fairly heavy bar 57, is loosely slidable on the posts 50, 50 to rest on the disc and prevent backlash of the paper, and parallel side guards 58, 58, depend from the shaft 55 to a guide roller or fixed rod 59 which connects blocks 60, 60 fixed on the posts 50 about midway between the axis of the disc and the top surface of plate 44. The guards constrain the unwinding ribbon 61 against running crooked, and the member 59 guides the run of the ribbon straight down into the cone 48.

A steam chamber is provided by a receptacle having a side wall 62 whose inturned annular flange 63 is bolted to the supplemental upright frame near its top 38. The wall 62 extends upwardly, enclosing the plate 44, cone 48, and that portion of the ribbon 61 which is below the member 59. A cover 64 is clamped on the posts 50, 50 between sleeves 65, 65, and the blocks 60, 60 so as to rotate with the plate 44 and the posts and substantially close the receptacle except for a small necessary clearance between the periphery of the cover and the wall 62 and except also for a narrow slot just below the member 59 which passes the ribbon 61. Steam is admitted to the chamber through a supply duct 66 and is discharged therefrom through a tube 67. To provide access to the interior of the chamber, a portion 68 of the cover 64 may be hinged to the body of the cover, as shown at 69.

In the operation of those parts of the machine

which have thus far been described, steam fills the chamber 62 to condition the paper strip for twisting, and the steam atmosphere is kept hot and dry by providing a constant supply to replace 5 that which is discharged through tube 61. This tube empties into a cup 70, supported in the supplemental upright frame which mounts the rotating parts and the cup contains a polishing die 71 aligned with die 48 for rubbing the cord 72 into 10 which the ribbon 61 has been twisted. As has been explained at the outset of this specification, it is desirable to lubricate the passage of the cord through the die 71, and I have also found that moisture applied to the surface only of this cord 15 just prior to its passage through the die materially improves the quality of its surface. Water condensing in the drain cup 70 supplies this moisture. The level of the water can be regulated by adjusting a stopcock 73 in a lower drain tube 74 20 which cooperates with an upper level drain tube 75 to discharge water from the cup 70.

It is of course necessary to provide means for pulling the cord 72 through the mechanism which has been described and for winding it on a reel. 25 I shall now proceed briefly to explain preferred forms of pulling and reeling instrumentalities.

After leaving the die 71 the cord passes over a pair of double grooved sheaves 76, 77, being looped completely around each, so that the friction of 30 the hold is sufficient to pull the cord through the dies when the sheaves are rotated. From the inner sheave 77 the cord passes through a guide 78 to a reeling mechanism which will be described hereinafter.

35 The sheaves are driven by a shaft 79 on which the sheave 77 is fast. This shaft has fast on it a sprocket 80 carrying a chain 81 which drives a similar sprocket 82 fast on shaft 83 which carries the other sheave 76. The shafts 79 and 83 are 40 journalled in the framing of the machine, as by bearings 84 and 85 for shaft 83, and bearings 86 and 87 for shaft 79. Shaft 83 is driven by its sprocket 88, whose chain 89 is trained over a smaller sprocket 90, which, along with larger sprocket 91 with which it is fast, is loose on shaft 79. A chain 92 drives sprocket 91 from a small sprocket 93 fast on main drive shaft 34. To recapitulate, therefore, shaft 34 drives the sheaves through sprocket 93, chain 92, connected sprockets 45 91 and 90 which are loose on shaft 79, chain 89, and sprocket 88 which drives sheave shaft 83, and the companion sheave shaft 79 is driven by chain 81 trained over sprockets 82 and 80.

It will be recognized from what has been said 55 and from the showing in the drawings that the sheave drive shafts turn much more slowly than main drive shaft 34. In practice, of course, the ratio of these two shafts is worked out to cooperate with the diameter of the sheaves and the ratio of bevel gears 43 and 47 to cause the cord to be pulled through the dies in synchronism with a desired tightness of twist.

The reeling mechanism comprises a shaft 94 formed in two halves, one journalled in pedestal 55 17 and the other in pedestal 19. The two halves are aligned axially and are connected by a known type of slip coupling designated generally 95. This coupling consists essentially of two juxtaposed wheels, each fast on the end of one of the 70 shaft halves. A friction band 96 disposed about the peripheries of the two wheels may be tightened or loosened by a screw 97, so that when the outer half of the shaft is driven at a constant speed the inner half may turn with gradually decreasing speed.

The inner half of the shaft carries a mandrel 98 with a pair of horns 99. Aligned with the mandrel and slidably in a sort of tailstock 100 mounted on pedestal 18 is a dead center spindle 101 which, like the mandrel, is inserted into the 5 bore of a reel 102 which becomes clamped between the mandrel and the spindle and which turns with the mandrel by torque of the horns 99 against the cross arms of the reel. As the reel fills with cord, slippage in the coupling 95 proceeds at an 10 increased rate, so that a constant rate of drive may be used, and this drive rate is of course sufficient to keep slack out of the run of cord between the reel and the guide 78 at all times, even when the diameter of the reeled cord is at 15 a minimum.

The reel mandrel is driven from shaft 79 by chain 103 which is trained over sprockets 104 and 105, fast on shaft 79 and the outer half of shaft 94, respectively. 20

To thread the cord from end to end of the reel so that the convolutions will be laid up in smooth layers, I provide mechanism which will now be described. From the guide 78 the cord passes through a generally similar guide 106 mounted 25 on a nut block 107 which is threaded on a long screw 108 having unthreaded end portions journalled in bearings 109 mounted on frame side 11 and on frame side 10, respectively, the latter bearing being positioned just inwardly of a short 30 upright 110 which rises from frame side 10 to bar 24. One unthreaded end portion of screw 108 extends through this upright. The block 107 is slotted to slide on a guide bar 111 which extends 35 between the frame sides, and it will be obvious that if the screw be rotated the block and its guide 106 will be driven transversely of the machine, which is lengthwise of the reel, in one direction or another depending on the direction of rotation of the screw. Mechanism is provided for 40 rotating the screw first in one direction and then in the other so as to lay the cord in smooth, full layers on the reel. The screw is rotated by chain 112 which is trained over a sprocket 113 on the outer half of shaft 94 and over sprocket 114 on 45 a stub shaft 115 journalled in the upright 110. Fast with sprocket 114 is a pinion 116, and below this pinion and spaced from it is a similar pinion 117 fast on the end of screw 108. A plate 118 is pivoted on the unthreaded end of screw 108 and 50 mounts two small meshing pinions 119 and 120. These small pinions are of a diameter which is larger than the space separating the pinions 116 and 117. The pinion 119 is meshed with pinion 117 and the pinion 120 is out of engagement with pinion 117. Since the plate 118 which mounts pinions 119 and 120 rocks on the axis of pinion 117, it is clear, as can be seen from Fig. 9, that when the plate is rocked pinions 117 and 119 will 55 remain meshed, while pinion 120 will move into and out of engagement with pinion 116. It will also be observed that, since pinion 119 is larger in diameter than the space between pinions 116 and 117, rocking of the plate to the left as viewed in Fig. 9 will not only disengage pinion 120 from pinion 116 but will mesh pinion 119 with pinion 116. Since pinion 116 is driven by sprocket 114 and chain 112, its driving effect on screw 108 will be righthand or lefthand depending on whether both pinions 119 and 120 are in the train, 60 as shown in Fig. 9, or the single pinion 119 meshes with both pinions 116 and 117, as will be the case if the plate 118 be rocked to the left from the position in which it is shown in Fig. 9.

65 A link 121 is connected at one end to the plate 70

75

to accomplish the required pushing and pulling action for reversing the screw. The other end of this link is pivoted to a short lever 122 fulcrumed at 123 on frame side member 10, and a second link 124 connects the other arm of this lever with a second lever 125 fulcrumed at 126 on a shelf 127 bolted on the member 10. This lever 125 rocks between stops 128, 129 formed on the shelf. Obviously, rocking of lever 125 from one stop to the other will operate the linkage to reverse the direction of rotation of the screw 108, as will be observed from a comparison of Figs. 7, 8 and 9, Figs. 7 and 8 showing the linkage in its two positions.

15 It is of course necessary to snap the linkage alternately from one position to the other as the cord convolutions approach the ends of the reel. This is accomplished by the rod 130 which is jointed at one end to the free end of lever 125 and which has its other end loose in a block 131 fast on the end of a push rod 132 which is slideable through a bearing 133 on the shelf 127 and through a finger 134 projecting from nut block 107. The push rod 132 extends transversely across practically the whole bed of the machine, immediately in front of the guide bar 111. Slidable stops 135, 136 are adjustable on the push rod by set screws, and are arranged to be engaged by the finger 134 in its traverse across the machine so 30 that the rod 132 will reciprocate to move the block 131 between its Fig. 7 and Fig. 8 positions. A compression spring 137 around rod 130 between block 131 and the free end of lever 125 serves to bias the lever strongly against one or the other 35 of stops 128, 129 until movement of rod 132 carries rod 130 and lever 125 past dead center, whereupon expansion of spring 137 quickly snaps lever 125 from engagement with one of the two stops into engagement with the other. The manner 40 in which this movement of lever 125 is transmitted to plate 118 and the resulting effect on the direction of rotation of screw 108 will, it is thought, be clear from what has been said in explanation of the figures and from the figures themselves, 45 particularly Figs. 7, 8 and 9.

It is believed that the operation of the machine will be evident from the foregoing description. It will be recognized that the machine is entirely automatic, so that a number of them can be arranged in a battery under the attention of a single operator. The very dry reeled product is superior to the best prior art cord known to me. It can be put to immediate use for any purpose for which such cord is commonly employed, or 55 it can be stored indefinitely without danger of mould or change in its properties or condition resulting from evaporation of moisture.

As explained in the foregoing specification and as pointed out in the appended claims, the invention is said to be concerned with the production of cord from paper strip by a steam treatment. These terms are not to be strictly construed. Thus, the "cord" may be a stout rope, a thin yarn, a stiff reed, or other generally analogous body. The term "paper" includes all equivalent strip material that can be hot steamed to effect softening without swelling. The steam is not necessarily generated from water or water alone, but the term is intended to include the vapor 70 phase of other normal liquids and solids as well which may be introduced at high temperature into the steaming chamber to introduce into the strip, in addition to the required softness, some other specially desired property, such as color, 75 lustre, lubricity, etc. Various changes from the

described embodiment of the invention will suggest themselves to those skilled in this art who require special types of product.

I claim:

1. A method of twisting a paper strip into cord 5 form which includes twisting the strip in an atmosphere of live steam and pulling the twisted cord through a forming die while still subjected to said atmosphere.

2. A method of twisting a paper strip into cord 10 form which includes twisting the strip in an atmosphere of live steam and immediately thereafter subjecting the twisted cord to circumferential rubbing and polishing contact with a forming die while maintaining the cord in said atmosphere. 15

3. A method of twisting a paper strip into cord form which includes passing the strip into a chamber, maintaining an atmosphere of live steam in said chamber, twisting the strip into cord form in said chamber, and pulling the cord 20 out of said chamber through a polishing and forming die.

4. A method of twisting a paper strip into cord form which includes maintaining an atmosphere of live steam in a chamber, passing the strip 25 through said chamber sufficiently fast substantially to prevent the strip absorbing water, and twisting the strip into cord form while in the chamber.

5. A method of twisting a paper strip into cord 30 form which includes maintaining an atmosphere of live steam in a chamber, passing the strip through the chamber and simultaneously twisting the strip sufficiently fast substantially to prevent wetting of the interior of the cord, and thereafter pulling the cord through a polishing and forming die while subjecting its outer surface to a moistening agent. 35

6. A method of twisting a paper strip into cord form which includes maintaining an atmosphere 40 of live steam in a chamber, passing the strip through the chamber and simultaneously twisting the strip sufficiently fast substantially to prevent wetting of the interior of the cord, immediately thereafter pulling the cord through a polishing 45 and forming die, discharging steam from the chamber, and directing said discharge, as wet steam and water vapor, on to the cord just anterior to its passage through the die.

7. A method of twisting a paper strip into cord 50 form which includes maintaining an atmosphere of live steam in a chamber, passing the strip through the chamber and simultaneously twisting the strip sufficiently fast substantially to prevent wetting of the interior of the cord, and immediately thereafter pulling the cord through a polishing 55 and forming die while wetting the exterior only of the cord.

8. A machine for twisting a paper strip into cord form comprising a receptacle forming a 60 steam chamber, means mounting a roll of paper strip adjacent the chamber, means supplying steam to the chamber, means pulling the strip through the chamber, and means twisting the strip in the chamber. 65

9. A machine for twisting a paper strip into cord form comprising a receptacle forming a steam chamber, means supplying steam to the chamber, means rotating within the chamber, a die fixed in the rotating means, means mounting 70 a roll of paper strip on the rotating means, and means pulling the strip from said roll through said die while the mounting and rotating means are rotating together.

10. A machine for twisting a paper strip into 75

cord form comprising a support having an opening, a plate mounted for rotation on the support and provided with an opening located in the line of its axis of rotation and aligned with the opening in the support, a casing enclosing the plate to form a steam chamber, means carried by the plate to mount a roll of paper strip, means driving the plate to twist the strip in the steam chamber, and means pulling the twisted strip through said openings.

11. A machine for twisting a paper strip into cord form comprising a support having an opening, a plate mounted for rotation on the support and provided with an opening located in the line of its axis of rotation and aligned with the opening in the support, a casing surrounding the periphery of the plate and a cover mounted on and spaced from the plate whereby said support, casing and cover cooperate to form a generally closed steam chamber containing the plate, means carried by the plate and projecting beyond the cover to mount a roll of paper strip, means driving the plate to twist the strip in the chamber, and means pulling the twisted strip through said openings.

12. A machine for twisting a paper strip into cord form comprising a vertical support having an upwardly facing socket provided with a central opening, a plate having a central hub rotatably mounted in said socket and having an axial opening aligned with the opening in the socket, a casing mounted on the support surrounding the plate and having an open top, a closure for the top of the casing carried by the plate and cooperating with the casing to provide a steam chamber, means for supplying steam to said chamber, means carried by the plate and extending through the closure to mount a roll of paper strip above the closure, means for pulling the strip through a slot in the closure and through said aligned openings, and means driving the plate to twist the strip in the chamber.

13. A machine for twisting a paper strip into cord form comprising a vertical support having an upwardly facing socket provided with a central opening, a plate having a central hub projecting into said opening and provided with gear teeth and having an axial opening, portions of the socket and plate about the periphery of the hub cooperating to support the plate for rotation in the socket, a casing mounted on the support surrounding the plate and having an open top, a closure for the top of the casing carried by the plate and cooperating with the casing to provide a steam chamber, means for supplying steam to said chamber, means carried by the plate and extending through the closure to mount a roll of paper strip above the closure, means for pulling the strip through a slot in the closure and through said openings, and a gear journaled in the support and engaging the hub teeth for rotating the plate to twist the strip in the chamber.

14. A machine for twisting a paper strip into cord form comprising a receptacle forming a steam chamber, means mounting a roll of paper strip beyond one side of the chamber, a forming and polishing die beyond the other side of the chamber, means for pulling the strip through the chamber and thereafter through said die, means for twisting the strip in the chamber prior to its

passage through the die, means supplying steam to the chamber, and means draining steam from the chamber and directing said drained steam on to the twisted strip at the point of its passage through the die.

5

15. A machine for twisting a paper strip into cord form comprising a receptacle forming a steam chamber, means mounting a roll of paper strip beyond one side of the chamber, a forming and polishing die beyond the other side of the chamber, a cup surrounding said die, means for pulling the strip through the chamber and thereafter through said cup and die, means for twisting the strip in the chamber prior to its passage through the cup, means supplying steam to the chamber, and means draining steam from the chamber and directing said drained steam into the cup.

10

16. A machine for twisting a paper strip into cord form comprising a receptacle forming a steam chamber, means mounting a roll of paper strip beyond one side of the chamber, a forming and polishing die beyond the other side of the chamber, a cup surrounding said die, means for pulling the strip through the chamber and thereafter through said cup and die, means for twisting the strip in the chamber prior to its passage through the cup, means supplying steam to the chamber, means draining steam from the chamber and directing said drained steam into the cup, and means regulating the discharge of said drained steam from the cup whereby a portion of said steam will condense in the cup and a predetermined quantity of water can be maintained therein.

20

17. A machine for twisting a paper strip into cord form comprising an upright frame having an upper cross member, a plate mounted for rotation on the frame, a die mounted on the plate and in its axis of rotation, a pair of standards mounted on the plate, bearings carried by the standards for journaling the shaft of a disc of rolled paper strip, means journaled in the upper cross member and connecting the standards, means pulling the strip through the die, and means rotating the plate to twist the strip.

18. A machine for twisting a paper strip into cord form comprising an upright frame having an upper cross member, a plate mounted for rotation on the frame, a die mounted on the plate and in its axis of rotation, a pair of standards mounted on the plate, bearings carried by the standards for journaling the shaft of a disc of rolled paper strip, means journaled in the upper cross member and connecting the standards, means pulling the strip through the die, means rotating the plate to twist the strip, and a weight vertically slidably on the standards and bearing on the disc to retard the unrolling of paper strip therefrom.

19. A machine for twisting a paper strip into cord form comprising a heavy plate capable of acting as a flywheel, means for rotating the plate about a vertical axis, a die carried by the plate in the line of its axis of rotation for passing the twisted cord, posts rising from the plate, and a horizontal spindle carried by the posts for mounting a disc of strip paper substantially symmetrical to the axis of the plate.
